UNITED STATES PATENT OFFICE.

GEORGE E. CHATILLON, OF NEW YORK, N. Y.

DESIGN FOR A SCALE-DIAL.

46,245.

Specification for Design.

Patented Aug. 11, 1914.

Application filed May 29, 1914. Serial No. 841,924. Term of patent 14 years.

To all whom it may concern:

Be it known that I, GEORGE E. CHATILLON, a citizen of the United States, residing at New York, in the county of New York and State of New York, have invented a new, original, and ornamental Design for a Scale-Dial, of which the following is a specification, reference being had to the accompanying drawing, forming part thereof.

Figure 1 is a front view, and Fig. 2 is a cross section.

The novel feature of the design is, first, the concentric arrangement of contrasting

grounds, with the scale divisions and intermediate numerals on the outer ground, and large numerals on the inner ground; and secondly, the configuration of the dial substantially as shown.

I claim:

The ornamental design for a scale dial, substantially as shown and described.

GEORGE E. CHATILLON.
